United States Patent Office

Des. 233,597
Patented Nov. 12, 1974

233,597

PACKAGE OF FORKS OR THE LIKE

Samuel R. Davis, Jr., and Harry A. Watson, Federalsburg,
Md., assignors to Ipcos Hospital Supply Corporation,
Valhalla, N.Y.

Filed Sept. 13, 1972, Ser. No. 288,695

Term of patent 14 years

Int. Cl. D9—99

U.S. Cl. D9—193

FIG. 1 is a plan view of a package of forks or the like showing our new design;

FIG. 2 is a side elevational view thereof;

FIG. 3 is an end elevational view thereof; and

FIG. 4 is a fragmentary perspective view thereof.

The side opposite the side shown is plain.

We claim:

The ornamental design for a package of forks or the like, substantially as shown and described.
